2,056,672

WATER-COOLED HOUSING FOR
PYROMETER DEVICES

William C. Hogg, Pittsburgh, and Thomas C. King, Munhall, Pa., and Lewis Rumford, 2d, Wilmington, Del., assignors to United States Steel Corporation, a corporation of New Jersey

Application July 16, 1935, Serial No. 31,737

2 Claims. (CL 73—32)

This invention relates to radiation pyrometer devices and more particularly to a cooling housing therefor. The radiation sensitive element of such pyrometer devices is particularly susceptible to and deleteriously affected by heat radiation. Heretofore in the art it has been proposed to provide means including a cooling housing whereby the radiation sensitive element is protected from deleterious heating. Such cooling 5 housings as have heretofore been proposed however have been designed to maintain the entire pyrometer device at a fairly uniform temperature from one end to the other.

This is frequently undesirable where water 10 cooling is used since the radiation sensitive element is operated at temperatures below which water vapor and hydrocarbon vapors condense. Under these conditions a liquid condensate deposits upon mirror, window, or lens surfaces 15 within the element thereby making unreliable temperature readings.

In the normal use of such a pyrometer device, particularly in the measuring of furnace temperatures by the practice of the invention disclosed and claimed in copending application Serial No. 31,735, filed July 16, 1935 entitled Radiation pyrometer installation, by Lewis Rumford II, one of the co-inventors of the present invention, the open end or nose of the pyrometer only 20 is subjected to or exposed to excessive heating. By eliminating the excessive heating at this point air cooling of the remainder of the device is found to be effective in holding the temperature of the radiation sensitive element within the desired 25 range to prevent overheating and to prevent condensation of liquid upon the surfaces of the instrument.

One of the objects of the present invention is 30 to provide a cooling housing for a radiation pyrometer device in which the open end of the device is preferentially cooled over the remainder. Another object is to provide means to protect the nose of the radiation pyrometer device from overheating and to prevent the condensation of 35 water vapor and hydrocarbon vapors within the said device. Still another object of this invention is to provide an improved cooling housing for a radiation pyrometer device. Other objects and advantages will become apparent as the 40 invention is more fully disclosed.

In accordance with the above objects we have 45 devised a cooling housing in which means are provided to water cool the open end of the pyrometer device and to air cool the remainder thereof, and in combination therewith we have

provided a shutter element for closing the open 5 end of the housing and pyrometer when desired to prevent the entrance into the housing of dirt and dust particles.

Before further disclosing the present invention 10 reference should be made to the accompanying drawing wherein:

Fig. 1 illustrates the usual relative positioning 15 of a radiation pyrometer device with respect to a furnace in its commercial use;

Fig. 2 is a side elevation of the cooling housing 20 of the present invention;

Fig. 3 is an open end view of the same; and

Fig. 4 is a longitudinal section along plane 25 4—4 of Fig. 3.

Referring to the drawing, as indicated in Fig. 1 the radiation pyrometer 1 is positioned with its open end towards the furnace 2 and in axial alignment with the bore 3 in the furnace wall 4. Bore 3 as disclosed in the above identified co-pending application is angled vertically upward 30 so that the radiant energy emitted from the inner surface 5 of the roof of furnace 2 may be measured by the pyrometer 1. Furnace 1 as illustrated is a cross-sectional view of a typical open hearth furnace. Molten bath 6 on hearth 7 is heated by the heat energy of burning gases passing 35 thereover from burner 8 disposed in one end. A second burner (not shown) is disposed in the opposite end of the furnace.

As may be readily seen from Fig. 1 the open 40 end of the pyrometer device 1 only is subjected to excessive heating. The remainder of the device becomes heated mainly by conduction from this end. In accordance with the present invention 45 cooling housing 10 (Figs. 2, 3 and 4) is provided with means to preferentially cool the open end of the pyrometer leaving the remainder of the housing to cool naturally in the open air. Thus the mirror concentrating radiation upon the radiation sensitive element 11 (Fig. 4) of the pyrometer device 1 is protected from the condensation 50 of water and hydrocarbon vapors thereon.

Referring to Figs. 2, 3 and 4, the cooling housing 55 of the present invention consists substantially of a tubular element 10 having an inside diameter approximating the outside diameter of the radiation pyrometer having at one end a chamber 12 provided with inlet and outlet openings or ports 13 and 14 respectively. The size and cooling capacity of chamber 12 may be varied widely without departing from the present invention depending in part upon the intensity of the heating effects to which the open end 13 of the pyrometer element may be subjected and upon the pressure

of water passing through chamber 12. The opposite end 15 of the cooling housing 10 may be belled out substantially as indicated at 15 to provide clearance for terminals 16 of the said pyrometer.

In the ordinary use of such a pyrometer in connection with an open hearth furnace the open end of the pyrometer is sighted through opening 3 of the furnace, as indicated in Fig. 1. During operation of the furnace as soon as each heat is tapped the refractory lining of the furnace hearth 7 is relined with refractory materials which are shoveled thereupon. The force of shoveling propels particles of the refractory material through the opening 3 in the furnace back wall. The particles of refractory material fall into the open end of the pyrometer, clouding the mirror element thereof and deleteriously affects the responsiveness of the device.

To eliminate this condition we provide shutter element 17 keyed adjacent its edge to one end of rotatable shaft 18 mounted in bearings 19 on housing 10. Lever arm 20 is provided on the opposite end of shaft 18 to rotate the shutter into and out of end closing position on housing 10.

From the above description of the present invention it is apparent that many modifications and adaptations may be made therein without departing essentially from the nature and scope thereof as may be included within the following claims.

What we claim is:

1. In combination, a radiation pyrometer device including a tubular container having an open end and a closed end with a radiation sensitive element disposed adjacent the closed end, a tubular cooling housing enclosing said device including means to water cool the open end of said tubular container for a determined distance back towards the closed end but not the closed end thereof and a shutter element mounted upon said housing adapted to protect the open end of said device and housing from the entrance of dirt and debris therein.

2. In combination, a radiation sensitive device including a tubular container having an open end and a closed end and a radiation sensitive element disposed adjacent the closed end with means to concentrate a beam of radiation entering the open end upon the said element, and a cooling housing for said device, said housing being provided with fluid cooling means to absorb heat radiation falling directly upon the open end of said device and with means to permit air cooling of the closed end of said device and the said radiation sensitive element and beam concentrating means enclosed thereby.

CERTIFICATE OF CORRECTION.

Patent No. 2,056, 672.

October 6, 1936.

WILLIAM C. HOGG, ET AL.

It is hereby certified that the above numbered patent was erroneously issued to "United States Steel Corporation" as assignee of the entire interest in said invention, whereas said patent should have been issued to William C. Hogg, Thomas C. King, and Lewis Rumford, II, said Rumford assignor to United States Steel Corporation, a corporation of New Jersey, as shown by the record of assignments of this office. In the grant, line 2, and in the heading to the printed specification, line 5, for "Lewis Rumford, 2d" read Lewis Rumford, II; and that the said Letters Patent should be read with these corrections therein that the same may conform to the record of the case in the Patent Office.

Signed and sealed this 22nd day of December, A. D. 1936.
